ACROBATIC TOY

Archibald A. Mercola and Paul D. Tetrick,
Beverly Hills, Calif.

Application May 19, 1952, Serial No. 288,694

2 Claims. (Cl. 46—133)

1

This invention relates to improvements in acrobatic toys.

An object of the invention is to provide an improved acrobatic toy consisting essentially of a base, a pair of standards on the base, a horizontal bar rotatably mounted on the standards, and a figure mounted on the bar so as to be swung thereby as the bar rotates.

The improved acrobatic toy has a novel means by which the bar may be rotated so that it may be forcibly rotated in either direction and then allowed to coast or to continue to rotate freely whereby the figure will be caused to go through various gyrations or animations.

With the foregoing and other objects in view, which will be made manifest in the following detailed description and specifically pointed out in the appended claims, reference is had to the accompanying drawing for an illustrative embodiment of the invention, wherein:

Figure 1 is a perspective view of the improved acrobatic toy; and

Fig. 2 is a vertical section taken substantially upon the line 2—2 upon Fig. 1.

Referring to the accompanying drawings wherein similar reference characters designate similar parts throughout, the improved toy comprises a suitable base 10 on which two tubular standards 11 and 12 are rigidly mounted. At the upper ends of these standards there are forwardly extending ears 13 which provide bearings for a horizontal bar 14. The horizontal bar 14 is rotatably mounted in the bearings and adjacent one end it has rigidly secured thereto a pinion 15. This pinion is engageable by a rack 16 that is vertically slidable in the standard 11. The rack adjacent its lower end is equipped with a downwardly extending stem 17 to which is secured a handle 18. This handle protrudes through a vertical slot 19 in the standard 11. The rack is urged into its uppermost position by means of a coil compression spring 20 disposed within the standard 11 and which is compressed between a spring seat 21 and a washer 22 that is fixed within the standard 11 above the upper end of the slot 19. The upper end of the rack may be equipped with a weight 23 which tends to smooth out the action of the compression spring 20. The use of this weight, however, is optional.

Adjacent the upper end and adjacent the lower end of the rack 16 teeth are omitted as indicated at 24 and 25 so that when the rack is at the ends of its stroke the pinion 15 in effect is disengaged so that the pinion and consequently the bar 14 can coast or rotate freely.

2

On the bar 14 there is mounted a flexible or jointed figure 26 shown as being attached to the bar by its arms or hands. This figure is fixedly attached to the bar on one side thereof although the torso and legs of the figure may be flexible or jointed. The weight of the figure is counterbalanced by a counterweight 27 mounted on an arm 28 that is rigidly attached to the bar and which extends therefrom on the opposite side from the figure 26.

When the handle 18 is manually depressed the teeth of the rack 16 engage the pinion causing the pinion and consequently the bar 14 to be forcibly rotated. This causes the figure 26 to be swung about the bar 14 as an axis. When the rack 16 is fully depressed the pinion 15 is opposite the portion 24 and is consequently released by the rack. This permits the bar 14 to rotate freely and, in effect, coast to a stop. When the bar is forcibly rotated the figure 26 is swung outwardly from the bar by centrifugal action but as the bar coasts to a stop the flexible or jointed legs on the figure may cause the figure to go through various amusings gyrations or animations. If the handle 18 is released the compression spring 20 is effective to elevate the rack 16, rotating the bar 14 in the opposite direction. This causes the figure 26 to be oppositely swung and when the pinion is opposite the portion 25 the bar 14 is again released to coast to a stop.

From the above described construction it will be appreciated that the improved acrobatic toy is of relatively simple and durable construction and that it may be easily operated. In the course of its operation the figure is forcibly swung or rotated during a major portion of the stroke of the rack 16. However at the ends of the stroke of the rack 16 the bar 14 is released or disengaged so that it may coast to a stop.

Various changes may be made in the details of the construction without departing from the spirit and scope of the invention as defined by the appended claims.

We claim:

1. An acrobatic toy comprising a base, a pair of spaced tubular standards on the base, one of said standards having a slot formed therein adjacent the base, U-shaped bearings on the free end of each standard, a bar rotatably supported by said bearings parallel to the base, a flexible figure fixedly attached to the bar, a pinion on the bar and within the confines of one bearing, a rack slidable within said one standard engageable with said pinion to rotate the pinion and bar, a stem on the rack, a spring about the stem to urge the rack to the uppermost position, a le-

ver on the stem extending outwardly through the slot in said standard by which the rack may be depressed, said rack at certain locations having teeth omitted therefrom in order that the pinion may be disengaged to permit the bar to freely rotate.

2. An acrobatic toy comprising a base, a pair of spaced tubular standards on the base, a bearing on the free end of each standard, a bar rotatably supported by said bearings, a flexible figure fixedly attached to the bar, a pinion adjacent one end of said bar, a rack reciprocable within one of said standards and in engaging relationship with said pinion for rotating said pinion and said bar, said rack having teeth omitted therefrom in order that the pinion may be disengaged to permit the bar to freely rotate, a stem on said rack, a spaced washer and seat on said stem, a coil spring about the stem and between said washer and seat for urging the rack to the uppermost 20

position, a handle on said stem adjacent said seat for actuating the rack, and a weight on the rack in opposed relationship to said handle.
